CHARLES H. JOCKMUS, OF ANSONIA, CONNECTICUT.

DETONATING-FUSE.

1,232,040.

Specification of Letters Patent.

Patented July 3, 1917.

Application filed March 20, 1916. Serial No. 85,314.

To all whom it may concern:

Be it known that I, CHARLES H. JOCKMUS, a citizen of the United States, residing at Ansonia, county of New Haven, State of Connecticut, have invented an Improvement in Detonating-Fuses, of which the following is a specification.

This invention has for its objects to provide a novel detonating base fuse for projectiles, more especially minor caliber projectiles such as are used for quick firing guns, which shall be thoroughly reliable and will make the projectile perfectly safe to handle, so that it will stand the test of dropping many times without danger of explosion and the fuse still remain operative, and which may be produced at a mere fraction of the cost of this class of fuses as ordinarily made.

With these and other objects in view, I have devised the novel fuse which I will now describe, referring to the accompanying drawing forming a part of this specification, and using reference characters to indicate the several parts:

Figure 1 is an elevation of my novel fuse ready for assembling;

Fig. 2 a plan view corresponding therewith;

Fig. 3 an inverted plan view;

Fig. 4 a longitudinal section on the line 4—4 in Fig. 1, looking in the direction of the arrows;

Fig. 5 an elevation of the firing pin detached;

Fig. 6 a detail sectional view on an enlarged scale, the section line being at right angles to that in Fig. 4;

Fig. 7 a section on the line 7—7 in Fig. 6, looking in the direction of the arrows;

Fig. 8 a view corresponding with Fig. 6, showing the firing pin and segments in the detonating position;

Fig. 9 a section on the line 9—9 in Fig. 8, looking in the direction of the arrows;

Fig. 10 a view of the segment spring detached, and

Fig. 11 is a detail view, partly broken away, showing the operation of the spring in retaining the segments in their normal position.

20 denotes the body of the fuse which is provided with an internal shoulder 21 against which the inner end of the cap 50 rests. The outer end of the cap tapers forward and inward slightly, and the cap is

securely retained in place against the shoulder by closing the open end of the body inward upon the cap, as clearly shown. The cap is provided with the usual pocket to receive a primer 23. Upon the inner face of the cap are segments 24, one end of each segment being pivoted on a pin 25 which extends entirely through the cap and is headed upon its outer end to prevent the possibility of its being pulled out by the shock of firing. The segments are shown as crescent shaped and their pivotal points are diametrically opposite to each other, the free end of each segment being contiguous to the pivoted end of the other segment. The segments are provided in their outer faces with circumferential grooves which receive a C-shaped spring 26, which closes the segments together and retains them in their normal position, as in Figs. 6, 7 and 11. One end of the spring is provided with an inturned end 27 which engages a hole in one of the segments near its free end, the other end of the spring lying in the groove of the other segment in which it may slide freely. 28 denotes the firing pin which is provided with a shoulder 29 and with a relatively heavy weight 30 to insure detonation of the primer upon impact, as will be more fully explained.

In assembling, the firing pin is dropped into the body, the segments are pivoted to the cap, the spring placed in position, a primer seated in the pocket in the cap, and then the cap is set in place against the shoulder on the body and secured in place by closing the outer end of the body inward upon the cap.

Fuses of this class are inserted in the bases of the projectiles and detonate upon impact. The projectiles are often fired at the rate of 150 a minute, have a velocity of 2000 feet per second or more, and are expected to pass through a $\frac{1}{16}$ inch steel plate and explode within six feet of the plate. The explosion is effected as follows: When the shot is fired and the projectile takes the rifling of the gun barrel, the centrifugal force of the projectile causes the segments to separate, i. e. open outward, overcoming the strength of the spring, which is relatively light, so that the firing pin is released and may pass between the segments. Upon impact, the velocity of the projectile is checked, and, the firing pin being loose therein, the blow of the firing pin upon the primer det-

onates it and the flame, passing through a hole or holes in the cap, ignites the explosion charge of the projectile. It should be borne in mind that the spring, while relatively light, is sufficiently strong to retain the segments closed inward under all conditions except the centrifugal force generated by the rotation of the projectile after it takes the rifling of the gun barrel. Under all other conditions, the segments remain closed inward, as in Figs. 6, 7 and 11, so that the shoulder of the firing pin cannot pass the segments and the possibility of detonation of the primer by the firing pin is avoided.

Having thus described my invention, I claim:—

1. A fuse of the character described comprising a body having an internal shoulder, a cap engaging the shoulder and secured in place by closing the end of the body inward, segments carried by the cap, a con-

tractile spring for moving the segments inward, said spring being located in grooves in the segments, and a firing pin normally retained out of detonating position by the segments and adapted to be released when the segments are separated by centrifugal force. 25

2. A fuse of the character described comprising a headed body, a cap within the head having a primer pocket, pins extending through the cap and headed on the outer side, grooved segments on the inner face of the cap pivoted on the pins, a C-shaped 35 spring therein which incloses the segments and is secured to one of them, and a firing pin having a shoulder which normally engages the segments to retain it out of detonating position but is released when the segments are separated by centrifugal force. 40

In testimony whereof I affix my signature.

CHARLES H. JOCKMUS.
